UNITED STATES PATENT OFFICE.

MABEL BURN, OF BEAUFORT, SOUTH CAROLINA.

COIN-HOLDER.

1,010,846.

Specification of Letters Patent. Patented Nov. 28, 1911.

Application filed February 24, 1911. Serial No. 610,657.

To all whom it may concern:

Be it known that I, MABEL BURN, a citizen of the United States, residing at Beaufort, in the county of Beaufort and State of 5 South Carolina, have invented certain new and useful Improvements in Coin-Holders, of which the following is a specification.

This invention relates to improvements in coil holders or packages of a permanent 10 character, which is particularly adapted for use by banks, counting houses and other business concerns which handle large sums of money.

The principal object of the invention is to 15 provide a cheap, durable and safe holder for coin in which the coin contained therein may be easily inserted or removed and will be almost entirely visible.

Another object is to provide a coin holder 20 adapted to hold coins of different denominations.

With the above and other objects in view, the present invention consists in the combination and arrangements of parts herein- 25 after more fully described, illustrated in the accompanying drawings and particu- larly pointed out in the appended claim, it being understood that changes may be made in the form, proportion, size and minor de- 30 tails without departing from the spirit or sacrificing any of the advantages of the invention.

In the drawings:—Figure 1 is a plan view of the invention in open position. Fig. 35 2 is an end view. Fig. 3 is detail view. Fig. 4 is an enlarged detail view.

Referring now more particularly to the drawings in which like reference characters 40 designate corresponding parts throughout the several views, 5 and 6 represent two

semicircular members, composed of parallel longitudinal frame bars 7 and 8 and connecting semicircular end bars 9 and 10, preferably of flexible spring material. The member 5 has its ends open, and the ends 45 of member 6 are closed by disks 11, which may be suitably connected to the semicircular end bars 10 as by means of spaced spring clamps 12 on the bars 10. The sides of the members 5 and 6 are inclosed by 50 flexible reticulated side walls 12' and 13 preferably composed of loosely woven spring wire fabric and which are stretched between and suitably secured to their respective frame bars. Hinges 17 connect 55 the semicircular members 5 and 6 together. A suitable spring pressed pivoted dog 14, carried by the member 5 is adapted to resiliently engage a catch 15 correspondingly located on the member 6 to retain the 60 holder in closed position. If desired a plate 16 may be provided upon which the amount of money contained in the holder may be inscribed.

Having thus described my invention, what 65 I claim is:

A coin holder comprising two semicircular members having connecting side and end bars, end disks secured to the end bars of one of said semicircular members, side walls 70 stretched between the side and end bars of each of said members, said side walls comprising a wire fabric.

In testimony whereof I affix my signature in presence of two witnesses.

MABEL BURN.
